UNITED STATES PATENT OFFICE.

HARVEY W. BELL, OF YONKEERS, NEW YORK, ASSIGNOR TO THE BELOYT CORPORATION, OF DOVER, DELAWARE; A CORPORATION OF DELAWARE.

FLUID-PRESSURE GENERATOR.

Application filed October 31, 1919. Serial No. 334,771.

To all whom it may concern:

Be it known that I, HARVEY W. BELL, a citizen of the United States of America, and a resident of Yonkers, Westchester County, 5 and State of New York, have invented certain new and useful Improvements in Fluid-Pressure Generators, of which the following is a specification, reference being had to the accompanying drawings, forming a part 10 thereof.

This invention relates to fluid pressure generators, and its object is to provide a simple and efficient power generator. Another object is to provide an apparatus for 15 generating pressure in a gas. Another object is to provide an arrangement for utilizing the heat and the pressure generated within the cylinder of an internal combustion engine for some further function than 20 that of running the engine. Another object is to inject a fluid into the cylinder of an internal combustion engine after the explosion therein for augmenting the volume of the exhaust gas and to store and make use of 25 these gases; and more particularly to inject water for the double purpose of augmenting the volume of the gas and cooling the engine. Another object is to provide a fluid pressure 30 system in which the pressure is generated as aforesaid.

These and other objects of the invention will appear in the following specification in which I will describe the invention, the novel features of which will be set forth in appended claims.

Referring to the drawings:

Figure 1 is a diagrammatic representation of a fluid pressure system which is made according to and embodies this invention. 40 Figure 2 is a sectional elevation of an apparatus for generating pressure in the manner herein disclosed, the section being taken on the line 2—2 of Figure 3.

Figure 3 is an elevation partly in section of the same apparatus, the view being taken at right angles to that shown in Figure 2.

Figures 4-11 are diagrams illustrating the relative position of parts of the apparatus during one cycle of its operation.

50 Figure 12 is a diagram showing the different angular positions of the eccentrics which drive the sleeve piston during the cycle illustrated in Figures 4-11, and Figure 13 is a similar diagram showing the angular

positions during the same cycle of the crank 55 to which the power piston is connected.

Figure 14 is fragmentary sectional elevation of a modified form of construction of one of the parts showing a water jacketed cylinder.

Like characters of reference designate corresponding parts in all the figures of the drawings.

20 designates the cylinder of a four-cycle internal combustion engine of novel construction. This rests on a base 21. It is provided with intake ports 22 with which is connected a carburetor 23. It also has exhaust ports 24 which are connected by a pipe 25 with a pressure tank 26. A check 70 valve 27 is interposed in the pipe 25. 28 is a water intake port through the wall of the cylinder between the inlet and exhaust ports. The cylinder is lagged as at 29 with a heat insulating material.

75 Within the cylinder is a sleeve piston 30. This has ports 31 which register with the intake ports 22 at certain parts of the cycle, ports 32 which cooperate with the exhaust port 24 and a port 33 which cooperates with 80 the water intake ports 28. 34 is a spark plug in the sleeve piston.

Brackets 35 project upwardly from the sleeve. A transverse rod 36 which passes through them is connected by connecting 85 rods 37 to be reciprocated by eccentric pins 38.

40 is a power piston which is arranged to reciprocate within the sleeve piston. Its connecting rod 41 is connected with the 90 crank pin 42 of crank shaft 43 which is rotatively supported in the base 21. Gears 44 on the crank shaft mesh with gears 45 which drive the eccentric pins 38 at one-half the speed of the crank shaft. Another gear 95 46 of the same diameter as that of gears 45 meshes with one of them and rotates the shaft 47 to which is affixed a snail shell cam 48.

In Figure 1 a translating device 60 is 100 shown connected with the pressure tank 25 by a pipe 61 in which is a manually actuated valve 62. A pressure regulator 63 is shown connected by its lever 64 and a rod 65 with a throttle valve 66 between the carburetor 23 and the cylinder 20.

This apparatus operates in the following manner: In Figure 4 the relative positions of

the parts at the completion of the exhaust stroke is shown. At this time, the crank pin 42 is at the uppermost part of its movement as indicated diagrammatically at 1 in Figure 13, so that the power piston 40 is at the upper end of its travel. The eccentric pins 38 are at this time in the position indicated diagrammatically at 1 in Figure 12, so that the sleeve piston 30 has started on its upward movement from the lowermost part of its stroke. These positions are such that the port 32 has just closed the exhaust port 24.

Figure 5 shows the start of the suction stroke. Power piston is in this position shown half way down, as indicated diagrammatically at 2 in Figure 13. The sleeve piston is now half way up in its stroke as indicated diagrammatically at 2 in Figure 12. Although sleeve port 33 is passing cylinder port 28, the suction is not sufficient to raise a spring pressed check valve 55 from its seat.

Figure 6 shows the end of a suction stroke. The power piston 40 is at the lowermost part 25 of its stroke as indicated diagrammatically at 3 in Figure 13, and the sleeve piston is three-quarters of the way up. In this position the sleeve port 31 is in register with the intake port 22, and an explosive mixture is 30 admitted to the cylinder through them.

Figure 7 shows the relative position of the parts at the start of the compression stroke. Here the power piston 40 is one-half way up as indicated diagrammatically at 4 in Figure 13 and the sleeve piston is at the upper end of its stroke as indicated diagrammatically at 4 in Figure 12. All of the ports are now closed.

Figure 8 shows the position of the parts at 40 the beginning of the working stroke. While in this position, the charge is fired by the spark plug 34. At this time the power piston is at the upper end of its stroke as indicated diagrammatically at 5 in Figure 13, 45 and the sleeve piston is quarter way down in its stroke as indicated diagrammatically at 5 in Figure 12. All of the ports are closed.

Figure 9 shows the relative position of the parts at the intermediate part of the expansion stroke. The power piston 40 is half way down in its travel, as indicated diagrammatically at 6 in Figure 13 and the sleeve piston 30 is half way down in its stroke as indicated diagrammatically at 6 in Figure 12. At this time the sleeve port 33 is in register with the water intake port 28.

While the engine pistons have been making these parts of their movement the snail shell cam 48 acting upon bell crank lever 53 60 has expanded spring 52 and held down the plunger of pump 50 by the connecting rod 54. This is the suction stroke of the pump. At the time the ports 28 and 33 register the abrupt shoulder of the snail shell cam passes 65 the part of the bell crank lever which is

pressed against this cam, and this allows the spring 52 to impart a sudden upward stroke to the pump plunger, thereby injecting through pipe 51 and the ports 28 and 33 a desired amount of water into the engine cylinder. The pump pressure is sufficient to raise a spring pressed check valve 55 from its seat.

This water is immediately changed into steam by coming in contact with the hot 75 gases of combustion. It also has a cooling effect upon the apparatus.

Figure 10 shows the relative position of the parts at the end of the expansion stroke and the beginning of the exhaust. In this case the power piston 40 is at the lowermost part of its travel as indicated at 7 in Figure 13, and the sleeve piston 30 is approaching the lower end of its travel as indicated at 7 in Figure 12. All of the ports are closed, 85 but the sleeve port 32 is beginning to open the exhaust ports 24.

Figure 11 shows the relative position of the parts at the intermediate part of the exhaust stroke. In this figure the power piston 40 is half way up its stroke as indicated diagrammatically at 8 in Figure 13 and the sleeve piston 30 is at the lowermost part of its stroke as indicated diagrammatically at 8 in Figure 12. The sleeve port 30 is now in full registry with the exhaust ports 24 and the combined gases of expansion and the steam are being forced out through these ports and through pipe 25 and check valve 95 27 into the pressure tank 26.

Referring again to Figure 4 in which the parts are shown at the end of the exhaust stroke, it will be seen that there is practically no clearance between the power piston 40 and the sleeve piston 30 at the time the 105 exhaust ports are closed. Therefore, practically all of the gas within the cylinder is ejected.

Relative positions of the parts are such that at the beginning of the explosion stroke 110 illustrated at Figure 8, there is a substantial distance between the power piston 40 and the sleeve piston 30 which forms the compression and combustion chamber.

When the pressure in tank 26 reaches the 115 predetermined amount, the regulator 63 will close the throttle valve 66 and slow down the engine.

The generated pressure may be utilized in any desired manner, for example,—translating device 60 may be a steam engine, the starting, speed and stopping of which may be controlled by manipulating the valve 62.

The lagging 29 shown in Figure 2 is used to conserve the generated heat but it may be omitted if desired. Figure 14 shows a water jacketed engine cylinder 20^A, the jacket of which is designated by 70. 71 is a pipe leading from this water jacket to the suction end of pump 50. By this arrangement 120 125 130

a part of the heat generated within the engine cylinder is absorbed in the water before it is injected into the cylinder. The water may be even heated into steam before it is injected. Or the heated water from the jacket may be led into pipe 25 as indicated at 72, to thereby cool the gases entering the pressure tank 60 and at the same time conserve the heat generated by the engine.

10 The invention upon which this application is based is broader than the specific embodiment thereof shown and described, which is more or less diagrammatical and used only for the purpose of illustrating a 15 way in which the invention may be used, and I, therefore, intend no limitations other than those imposed by the appended claims.

What I claim is:

1. A four cycle internal combustion engine comprising a cylinder provided with ports, a shaft, a reciprocatory sleeve in the cylinder closed at one end connected to be actuated by the shaft and provided with ports, a reciprocatory piston within the 25 sleeve and connected with the shaft, said sleeve and piston being arranged to open and close the ports and arranged to leave a combustion space between the top of the piston and the closed end of the sleeve at 30 the end of the compression stroke of the piston, to bring the top of the piston into close proximity with the closed end of the sleeve at the end of the exhaust stroke of the piston to effect complete scavenging, and 35 means for injecting water into the sleeve during the working stroke of the engine and after ignition of the charge therein.

2. A four cycle internal combustion engine comprising a cylinder provided with 40 ports, a shaft, a reciprocatory sleeve in the cylinder closed at one end connected to be actuated by the shaft and provided with ports, a reciprocatory piston within the sleeve and connected with the shaft, said 45 sleeve and piston being arranged to open and close the ports and arranged to leave a combustion space between the top of the piston and the closed end of the sleeve at the end of the compression stroke of the piston to bring the top of the piston into 50 close proximity with the closed end of the sleeve at the end of the exhaust stroke of the piston to effect complete scavenging, and a pump driven by the engine arranged 55 to inject water into the sleeve during the working stroke of the engine and after ignition of the charge therein.

3. An internal combustion engine comprising a cylinder provided with ports and 60 a shaft, a reciprocatory sleeve in the cylinder closed at one end connected to be actuated by the shaft and provided with ports, a reciprocatory piston within the sleeve and connected with the shaft, said sleeve and 65 piston being arranged to open and close the

ports and arranged to bring the top of the piston into close proximity with the closed end of the sleeve at the end of one of the strokes of the piston.

4. A four cycle internal combustion engine comprising a cylinder provided with ports and a shaft, a reciprocatory sleeve in the cylinder closed at one end connected to be actuated by the shaft and provided with ports, a reciprocatory piston within the 70 sleeve and connected with the shaft, said sleeve and piston being arranged to open and close the ports and arranged to leave a combustion space between the top of the piston and the closed end of the sleeve at 75 the end of the compression stroke of the piston, and to bring the top of the piston into close proximity with the closed end of the sleeve at 80 the end of the exhaust stroke of the piston to effect complete scavenging. 85

5. A four cycle internal combustion engine comprising a cylinder provided with ports, and a shaft, a reciprocatory sleeve in the cylinder closed at one end connected to be actuated by the shaft and provided with ports, a reciprocatory piston within the sleeve and connected with the shaft, said sleeve and piston being arranged to open and close the ports and arranged to leave a combustion space between the top of the piston and the closed end of the sleeve at 90 the end of the compression stroke of the piston, and to bring the top of the piston into close proximity with the closed end of the sleeve at 95 the end of the exhaust stroke of the piston to effect complete scavenging, means for injecting water into the sleeve during the working stroke of the engine and after ignition of the charge therein. 100

6. A four cycle internal combustion engine comprising a cylinder provided with ports and a shaft, a reciprocatory sleeve in the cylinder closed at its upper end, means for connecting the sleeve with the shaft to be reciprocated thereby at one half the 110 speed of the shaft through a shorter path than the stroke of the piston, said sleeve being provided with ports, a reciprocatory piston within the sleeve and connected with the shaft, said sleeve and piston being arranged to open and close the ports and arranged to leave a combustion space between the top of the piston and the closed end of the sleeve at the end of the compression 115 stroke of the piston, and to bring the top of the piston into close proximity with the closed end of the sleeve at the end of the exhaust stroke of the piston to effect complete scavenging, a pump actuated by the engine and connected with one of the cylinder ports arranged to inject water into the sleeve during the working stroke of the piston and after ignition of the charge 120 therein. 125

7. A four cycle internal combustion engine 130

comprising a cylinder provided with ports, and a shaft, a reciprocatory sleeve in the cylinder closed at one end connected to be actuated by the shaft and provided with 5 ports, a reciprocatory piston within the sleeve and connected with the shaft, said sleeve and piston being arranged to open and close the ports and arranged to leave a combustion space between the top of the 10 piston and the closed end of the sleeve at the end of the compression stroke of the piston, and to bring the top of the piston into close proximity with the closed end of the sleeve at the end of the exhaust stroke of 15 the piston, means for automatically introducing water into the sleeve during the working stroke of the engine and after ignition of the charge therein.

8. A four cycle internal combustion engine comprising a cylinder provided with ports, and a shaft, a reciprocatory sleeve in the cylinder closed at its upper end, means for connecting the sleeve with the shaft to be reciprocated thereby at one half the 25 speed of the shaft through a shorter path than the stroke of the piston, said sleeve being provided with ports, a reciprocatory piston within the sleeve and connected with the shaft, said sleeve and piston being arranged

to open and close the ports and arranged to 30 leave a combustion space between the top of the piston and the closed end of the sleeve at the end of the compression stroke of the piston, and to bring the top of the piston into close proximity with the closed end of 35 the sleeve at the end of the exhaust stroke of the piston to effect complete scavenging, a pump actuated by the engine and connected with one of the cylinder ports arranged to inject water into the sleeve during the 40 working stroke of the piston and after ignition of the charge therein.

9. A four-cycle internal combustion engine comprising a cylinder, a sleeve closed at one end and operating in said cylinder, a piston operating in the sleeve, the sleeve and cylinder having intake and exhaust ports registering in the intake and exhaust periods of the engine cycle and further having other ports registering when the intake and exhaust ports are closed during a part of the power stroke and means for introducing water under pressure through said registering ports when the intake and exhaust ports are closed. 50

In witness whereof, I have hereunto set my hand this 30th day of October, 1919.

HARVEY W. BELL. 55
